UNITED STATES PATENT OFFICE

LLOYD VAN SCIVER, OF CHESTNUT HILL, PENNSYLVANIA, ASSIGNOR TO J. B. VAN SCIVER CO., OF CAMDEN, NEW JERSEY, A CORPORATION OF NEW JERSEY

FLAP-SUPPORTING STRUCTURE FOR DESKS

Application filed November 15, 1927. Serial No. 233,360.

My invention relates to devices for supporting desk flaps when in open position and which are automatically thrown out of the way when the flaps are closed.

5 A further purpose is to accommodate mechanism for moving flap supports to position to the construction of the desk and flap so as to intrude as little as possible within the writing space of the flap and desk.

10 A further purpose is to seat a bar-operating lever and its attaching connections in the edge of the flap of the desk where the attaching connections for the lever may be used to finish two sides of a cut in the edge of the flap as distinguished from the three sides of a groove in the body of the flap of the desk.

15 The main purpose of my invention is to reduce the labor charge in applying operating parts to a desk flap for the support of the flap.

20 Further purposes will appear in the specification and in the claims.

I prefer to illustrate my invention by one construction only among various forms in which it might be applied, selecting a form 25 which is practical, effective, in application to the desks and quite inexpensive and which at the same time well illustrates the principles involved.

20 Figure 1 is a perspective view, partly broken away, showing a desk to which the preferred form of my operating mechanism is applied.

Figure 2 is an enlarged sectional perspective of a portion of Figure 1.

35 Figures 3 and 4 are vertical sections of desks similar to but not identical with Figure 1, taken across the flap and illustrating the mechanism in positions in which the flap is open and in which it is closed, respectively.

40 Figures 5 and 6 are fragmentary enlargements of parts of the construction seen in Figures 3 and 4.

45 Figure 7 is an end elevation of a fastening member seen in Figures 3, 4, 5 and 6.

In the drawings similar numerals indicate like parts.

The flap 10 is shown as pivoted to any type 50 of desk, typified by desks 11 and 11', so that the flap will open to the positions seen in

Figures 1 and 2 or will close to the position seen in Figure 4. When the desk is open it is very desirable to reinforce the hinge support by a sustaining bar 12 which is automatically thrown out beneath the flap by operation of parts attached to the flap. 55

The flap hinge 13 is secured to the flap by a strap 14 and to the desk by a strap 15. The strap 14 is conveniently used also as a pivotal attachment point 16 for a thrust rod 17 which is connected through a bracket 18 with the bar 12. 60

The rear portion of the desk is slotted at 19 to permit movement of the bracket 18 within it, so that the opening and closing of the desk causes movement of the bracket 18 toward the front or toward the rear, respectively, with consequent automatic movement of the bar 12 to a position in which its front end extends beneath the opening flap or to a bar position in which the front end is retracted within the desk and thus concealed, as seen in Figure 4. 65

As thus far described the structure is broadly old, many inventors having provided some attachment each of a bar similar to 17 to the flap with consequent withdrawal of a supporting bar to its position beneath the opening flap, and its return to its concealed position within the desk. 70

To the best of my knowledge where one of the hinge members has been used to support the pivot for a bar similar to bar 17 the hinge member used has been in the form of a channel which is adapted to fit within a groove in the flap of the desk, breaking up the otherwise unbroken finished surface of the desk flap and involving the work of quite a skillful cabinet maker in cutting and finishing of the groove in the flap so as to fit exactly to the channel and leave an unbroken edge on each side. This has been an expensive operation, not only without corresponding benefit but with actual injury to the flap in cutting into its table surface. 75

My invention is intended to secure all of the benefit of such a channeled construction without cutting the table surface of the flap, by placing the flap-engaging hinge member 14 in the edge of the flap as distinguished 80

from within the body of the table portion of the flap.

By locating the member 14 at the edge I am able to use an angle construction instead of requiring the channeled construction of the prior art and locate the member 15 within the extreme side edge of the desk space where it is concealed as much as possible by the side desk members 20 and 20'.

10 In applying my invention to the flap I cut the groove 21 in the edge of the flap to some such point as 22 corresponding in its distance from the hinge to the length of the strip 23 which is connected to hinge member 14. This 15 strip is preferably made from an angle rather than from a channel for the reasons merely that the two flanges 26 and 24 comprising the base parallel to the face of the flap and a flange at an angle thereto respectively are sufficient to finish the two edges 25 and 27 formed within the inner edge of the end of the flap by cutting the groove along this edge, rendering the additional side of the channel unnecessary and because the additional 20 (third) portion of the channel would detract from the appearance. The lateral wood edges 25 and the wood edges 27 parallel to the face of the flap are not only protected from mechanical injury by the flanges 24 and 26 of 25 the strip, but are screened from view by these flanges so that these wood edges of the groove need not be "finished."

By this construction but one lateral edge of the cut is bordered by the flap face (as distinguished from two such edges where the channel is to be seated in a groove) and the position of this edge laterally of the flap need not be as accurately set where it represents the side edge line of the flap as is the case where 40 it is the edge of one side of a groove whose total groove width must exactly match a channel width.

By making the thrust rod 17 rectangular I am able to use it to fill up the space within 45 the angle so that the angle and the bar together completely fill the space within the edge of the flap from which wood of the flap has been cut away.

With my construction it is still necessary 50 to cut grooves 28 in the desk surface but these grooves also are cut in the inner edge of the extreme ends of the table portions of the desk. Strips 29 are secured within these grooves and are connected with the opposite side of the hinge from that side with which strips 15 are connected.

The strips 29 are also most desirably angles 55 since there are but two faces of the grooves 28 to be protected. Angle flanges 30 protect the outwardly facing lateral surfaces 31 of the grooves and flanges 32 protect the upwardly facing surfaces 33 of the grooves. The ends 20 and 20' form the outer limits of 60 these grooves and require no protection.

The bars 17 fill the spaces within strips 29 just as they fill the spaces within strips 23.

The slots 19 are formed by cutting the entire edge away instead of cutting the depth of the groove only as in the front portion of the desk table edge. The outer walls of the slots 19 are thus also formed by the ends 20 and 20' which require no additional finish.

I thus secure unusual beauty of appearance and neatness with a minimum of work and of interference with the writing surface of the flap and desk table. The smaller amount of work required can be performed by operators having less skill than that required for fitting channels into the slots of the prior construction and the appearance of the flap and desk is much improved by the concealment of the mechanism within the body of the desk.

75 The strips 23 and 29 form casings for the cut wooden edges which receive the thrust bar. Their rigidity with the two parts of the hinges is preferably secured by making them integral with the respective hinge parts.

In view of my invention and disclosure variations and modifications to meet individual 80 whim or particular need will doubtless become evident to others skilled in the art, to obtain part or all of the benefits of my invention without copying the structure shown, and I, therefore, claim all such in so far as 85 they fall within the reasonable spirit and scope of my invention.

Having thus described my invention, what I claim as new and desire to secure by Letters Patent is:—

100 1. A desk, a flap hinged thereto and having a groove along each end at the inner edge of the flap, hinges for the flap, a metal casing for each groove covering the two otherwise exposed surfaces of the material of the flap, each supporting one end of the corresponding hinge, means for attaching the second end of each hinge to the desk table, a thrust rod pivoted at one end to the casing, a supporting bar for the flap and connections between the other end of the thrust rod and the supporting bar to operate the bar with movement of the flap.

105 2. A desk, a flap adapted to fold against the front of the desk and having grooves along the inner edges at the extreme ends of the flap, angles, one protecting the two faces of each groove, each secured to the flap, hinges for the flap, one member of each secured to an angle, and bars adapted to move in for concealment within the desk and out for support of the flap and thrust rods, pivotally connected to the flap at one end and connected with the bars through the surface of the 110 table of the desk at the other end to automatically shift the bars to the supporting and concealed positions.

115 3. In a desk flap support, a desk having ends extending above the table of the desk, the table being grooved in the front part at 120

the ends of the upper edges and having openings through the table in the rear part of the desk close to the ends, bars adapted to move parallel with the ends beneath the desk table and closely adjacent the ends for concealment in one position and flap support in another position, thrust rods pivotally connected with the bars to move the bars, a flap adapted to close the front of the desk and to open, the inner edges of the ends of the flap being grooved, metallic strips pivoted to the other ends of the respective thrust rods, covering the side and bottom faces of the edge grooves and secured to the flap, one member of each hinge being rigid with respect to one of the metallic strips, and other metallic strips rigid with respect to the other hinge members and fitting and covering the bottom and one side each of the grooves in the front of the desk table at the ends.

4. In a desk flap support, a desk having ends extending above the table of the desk, the table being grooved in the front part at the ends of the upper edges and having openings through the table in the rear part of the desk close to the ends, bars adapted to move parallel with the ends beneath the desk table and closely adjacent the ends for concealment in one position and flap support in another position, thrust rods pivotally connected at one end of each with one of the bars to move the bars, a flap adapted to close the front of the desk and open, the inner edges of the ends of the flap being grooved, metallic strips pivoted to the other ends of the respective thrust rods and having bases and flanges covering the bottom and side faces of the edge grooves and secured to the flap and one member of each hinge being formed by a flange of one of the strips and other metallic strips having flanges forming the other members of the hinges and fitting and covering the bottom and one side each of the grooves in the front of the desk table at the ends.
